UNITED STATES PATENT OFFICE.

CHARLES J. THATCHER, OF UPPER NYACK, NEW YORK.

METHOD OF EXHAUSTING VESSELS.

1,124,555.

Specification of Letters Patent.

Patented Jan. 12, 1915.

No Drawing.

Application filed March 11, 1910. Serial No. 548,677.

To all whom it may concern:

Be it known that I, CHARLES J. THATCHER, a citizen of the United States, and a resident of Upper Nyack, in the county of Rockland and State of New York, have invented certain new and useful Improvements in Methods of Exhausting Vessels, of which the following is a specification.

The process which constitutes this invention relates to the exhaustion of any vessels whatsoever in which it is desirable to rapidly and economically attain high vacua. It may be used either for exhausting electrical apparatus, which are permanently provided with electrical conductors or terminals, such as incandescent lamps, vacuum tubes, etc., or for exhausting non-electrical apparatus provided with suitable conductors or terminals only for the purpose of exhaustion.

The object of this invention is therefore to attain high vacua in any vessel requiring complete exhaustion, and the invention consists in effecting this in a rapid and economical manner by the use of non-volatilized and inexpensive gas absorbents.

It is well known that complete exhaustion of vessels to high vacua by mechanical pumping alone is a slow and somewhat costly procedure. The difficulty lies in the exhaustion of the last traces of gas.

My invention relates more particularly to the rapid removal of these last traces of residual gases remaining after mechanical exhaustion.

At the present time, so far as I am aware, the only process of rapid exhaustion is that used in the manufacture of incandescent lamps and set forth in U. S. Patent #537,693 to Arturo Malignani. Three steps are essential to the operation of this process. They are the preliminary mechanical exhaustion of the lamp to a pressure of about 2 mm. of mercury; the intensive incandescence of the filament of the lamp in this attenuated atmosphere and at a sufficient intensity to produce a characteristic faint bluish haze throughout the interior of the bulb; and lastly, the vaporization of a suitable solid substance, such as arsenic, iodin, sulfur, phosphorus, etc. previously deposited in some convenient locality within the interior of the lamp bulb. The process of said patent also comprises additional elements or steps which I consider tributary to the three fundamentally essential elements above re-

ferred to. These tributary steps have been modified in Letters Patent and in commercial practice, to some degree, as regards the means employed for carrying them out and the sequence of their performance. Otherwise the modern practice of incandescent lamp exhaustion is substantially identical with that devised by Arturo Malignani in 1894 and disclosed in his Letters Patent.

The herein described process differs from that just considered, in that I secure high vacua without volatilizing any substances, and also in that the intensive incandescence of the filament may, if desired, be dispensed with as an element of the process of exhaustion.

My process may be conveniently described as applied to the exhaustion of incandescent lamps. It is preferably used for the simultaneous exhaustion of a number of lamps or vessels—which is decidedly advantageous and economical—but may be used, if desired, for the exhaustion of a single vessel without deviations from the process as here described other than such as will be readily devised by workers in the art. After the lamps have been assembled and properly dried as is usual and by any means, I attach them to a vacuum pump or pumps of any description by which a sufficiently low pressure can be obtained. To the same pump or pumps I attach another air-tight vessel which is in free and uninterrupted communication with the pump and the lamp or series of lamps by a short system of tubing. This auxiliary vessel is provided with a suitable filament of carbon or metal, or with metallic terminals, by means of either or both of which an electric current of proper intensity and character can be conducted through the vessel. This vessel is also supplied in a manner hereinafter explained and before its attachment to the pump connections with a considerable quantity of a gas adsorbing solid, preferably one having a large superficial area as compared to its mass such as lamp black or charcoal. The gas from the entire system is adsorbed or absorbed by these substances in the auxiliary vessel. After once charging it with a considerable amount of a gas absorbent, the vessel may be used over and over again for a number of exhaustions without recharging or removing it from the pump connections. It is preferable to maintain the vacuum in the auxiliary vessel between exhaustions by

shutting off communication with the other part of the system by means of a pinch-cock upon a piece of rubber tubing or other suitable means.

The lamps and auxiliary vessel being thus prepared for exhaustion and attached to the pump or pumps, I thereupon evacuate the entire system to a suitable low pressure. During this preliminary mechanical exhaustion, it is advisable to pass an electric current through the filaments of all the lamps simultaneously and of a sufficient intensity to heat the filaments, the clamps which attach them to the leading-in wires, and any other interior portions of the lamps which may have occluded or which may generate gases, to a sufficient temperature to eliminate practically all of those gases. The object and method of doing this is well understood by workers in the art, since it is almost universally used in the exhaustion of lamps and is technically known as "working" the filament. Some incandescent lamps or other vessels which may be exhausted by my process may generate so little gas from these sources upon heating or upon the passage of the current that this working may be dispensed with.

A pressure which is suitably low, as hereinafter explained, having been attained by mechanical exhaustion, I shut off the communication with the pump or pumps by any suitable means, such as a pinch-cock upon a piece of rubber tubing in the main pump connection. If the pumps are provided with a practically non-leaking valve, this may be relied upon to effect the aforesaid closure. I now ionize or electrically excite the residual gases or a portion thereof in the auxiliary vessel by any suitable means, such as by the passage of a sufficiently strong electric current through the filament of the auxiliary vessel. The current employed must be of sufficient intensity to produce what is known as intensive incandescence of the filament, which is usually accompanied by the appearance of a characteristic faint bluish haze which at first practically fills the interior of the vessel but disappears as exhaustion proceeds. It is well known that the residual gases are ionized, mostly negatively, by this intensive incandescence. I prefer to secure this effect by passing an electrical current through the gases themselves by means of terminals with which the auxiliary vessel may be provided as already stated. The current necessary for this purpose will depend upon the final degree of exhaustion desired. The ionization of the residual gases immediately leads to a rapid reduction of gaseous pressure, not only in the auxiliary vessel but throughout the entire system of connections and lamps. The electrical resistance of the gaseous conductor in the auxiliary vessel accordingly varies

during the exhaustion and finally becomes very high. The voltage used must be sufficiently intense to overcome this resistance and produce a pronounced luminous discharge in the vessel practically until the desired final gaseous pressure is obtained. This point will be sharply indicated by the disappearance of the luminous manifestations in the same manner as when a solid conductor or filament is used. Any other means of ionizing the interior of the auxiliary vessel may be employed; and the residual gases in the lamps themselves may be preferably ionized at the same time by conducting a current of sufficient intensity through the filaments of all the lamps to produce the aforesaid characteristic faint bluish haze, now known to workers in the art as intensive incandescence.

The solid gas adsorbent or absorbent previously referred to, such as lamp black or charcoal, should be originally so deposited in the auxiliary vessel that the ionized gases are immediately exposed thereto. For this reason I prefer to deposit the gas absorbing solid so that it will be bombarded by the ions or ionized particles which are shot off from the filament of the auxiliary vessel or which traverse the space between the terminals when gaseous conduction is employed.

In the method of lamp exhaustion now in use, the gases are precipitated by a vaporizable solid, such as phosphorus, which is volatilized by heating, whereby the vapor of this solid substance is introduced into the lamp bulb; and it is this vapor, together with the ionization of the gases, which causes the precipitation of the gases and the attainment of the high vacuum.

In my process, the gases are removed by precipitating them upon non-vaporized solids which are preferably placed in a vessel connected with the lamp.

When the gas absorbing solid in the auxiliary vessel is struck by the ionized clusters of gaseous particles therein they are affixed, apparently by purely physical combinations, resulting as in the Malignani process in a rapid reduction of pressure. As the result of this removal of gaseous particles from the space within the auxiliary vessel other gaseous particles immediately flow into it from the lamps through the connecting system of tubing. These are in turn ionized and affixed. In this way practically all the gaseous particles of the residual gases originally in the auxiliary vessel, connecting tubing and the lamp bulbs, which particles were normally free and vibrating in all directions, become affixed and immovable. Since they thereby lose their energy and impact, the desired nullity of gaseous pressure, or an almost perfect vacuum, is attained in the entire system. Whether this explanation is correct or not, I find that

very high vacuum results upon the ionization of the gases. The auxiliary vessel and the lamps may then be shut off from the rest of the system by means of pinch-cocks

- 5 or other suitable means, the lamps are sealed off from their tubulatures by fusing the glass and the exhaustion is complete. The discarded tubulatures may then be withdrawn from the pump connections and the 10 tubules of an unexhausted batch of lamps inserted. Exhaustion then proceeds as before, except that the pinch-cock on the tubing leading to the auxiliary vessel is preferably not opened until mechanical exhaustion 15 of the lamp has been completed. In this way the amount of gas absorbed by the solid in the auxiliary vessel is restricted to those small amounts of residual gases remaining in the lamp bulbs and the connecting tubing after preliminary mechanical exhaustion. And the absorbing power of 20 solids of the class specified is so great that if a considerable quantity is introduced initially into the auxiliary vessel, recharging 25 is necessary only after a considerable number of exhaustions.

The gas absorbent solid may be introduced into the auxiliary vessel either through the tubulature in the case of a finely divided

- 30 solid, or if rather large portions of a substance like charcoal are used, through a suitably arranged air-tight gate or trap. It will be understood that if it is preferable to exhaust individual lamps or other vessels separately the gas absorbing solid may be introduced into the lamp itself or into the tubulature or portions connected to the lamps which may be sealed off after exhaustion. In this modification of my process 35 the ionization of the gases may be secured by intensive incandescence of the lamp filaments only, as indeed it may whenever the gases so ionized will come directly into contact with the gas absorbent. I may mention here that most if not all filaments apparently lose their ionizing power rapidly by prolonged intensive incandescence—at least a filament will not readily precipitate the gases after any considerably prolonged 40 use. Where filaments are relied upon to ionize the gases they must therefore either be new or must be so treated, by “flashing” for example, that their ionizing power is 45 restored to them.

- 50 My process is preferably operated by removing the bulk of the gases by mechanical exhaustion, down to a pressure of 1 to 2 mm. more or less, before precipitating the residual gases by ionization. Gases at 55 higher or lower pressures than these can be so precipitated when ionized by suitable means. When substantially new filaments are used there is no difficulty in producing sufficient ionization at all pressures from 2 mm. down. If ionization is produced by

gaseous conduction a potential of 2000 volts will be ample to start conduction at 2 mm. but will usually have to be increased somewhat, to say 3000 volts, toward the end of the exhaustion in order to secure a final 70 pressure of .020 to .010 mm. which is considered a sufficiently high vacuum for incandescent lamps.

From the foregoing description the manner in which my process may be applied to 75 the exhaustion of other vessels than incandescent lamps will be readily understood and carried out by workers in the art.

By exhausting vessels according to the herein described process certain practical 80 and important advantages result. Thus it is economical to dispense with the use of a suitable gas-absorbing substance in exhausting incandescent lamps. Although the process of exhaustion now employed requires the use of a very small amount of 85 a suitable substance such as phosphorus, the total cost of the same and of its deposition in the tubules of large numbers of lamps is considerable. By my process the 90 tubule can be made shorter, and the saving in glass tubing amounts to a further considerable item.

Incandescent lamp exhaustion by my process is also more economical than the 95 present practice in that it requires less attention on the part of the lamp operator and is, in reality, more rapid. A comparatively large number of lamps can be attached to each pump and the mechanical 100 exhaustion can then proceed while the operator is attaching or attending to another series of lamps. After the proper vacuum has been reached, as ascertained if desirable by a reading of the pressure by means of a 105 suitable gage attached to each series of lamps, the gases in the auxiliary vessel or the lamps can then be ionized. A determination of the pressure common to all the lamps can be made in a very few seconds by 110 the said gage to insure that the requisite high vacuum has been attained, or the disappearance of the blue haze may be relied upon to determine this point. By a suitable arrangement of gas jets the lamps may then all be 115 sealed off simultaneously. The exhaustion of a bank of twenty or more lamps in this manner will not occupy ten minutes all together, allowing even as much as five minutes for mechanical exhaustion during 120 which the operator's attention can be given to another series of lamps. This method of procedure, rapidity of exhaustion and output per operator cannot be duplicated by the present practice of lamp exhaustion, as each 125 lamp requires individual attention and treatment on the part of the operator during the critical portion of the exhaustion.

The gases are precipitated by my process in a more stable and prominent form of com- 130

bination than that which results by the present practice and outside of the lamp itself. The substance, phosphorus, which is now used, and which holds the gas in physical combination is vaporized in the lamp bulb at comparatively low temperatures, sufficiently low to liberate some of the gas with which it is combined. The temperature which will produce this effect is easily reached in actual use, particularly after the lamp has been used for some considerable time. The conditions under which the combination of the residual gases with phosphorus originally occurred is not duplicated in actual use. This effect when once started is cumulative and results in a considerable reduction in the useful life of the lamp. This effect cannot occur when my process is used, for the gases are precipitated in combination with practically non-vaporizable particles such as carbon, and outside of the lamp itself so that they are effectually and permanently removed from the lamp interior.

25 I claim:—

1. The process of rapidly producing high vacua in vessels, which consists in subjecting them to a suitable preliminary, mechanical exhaustion, and absorbing the residual gas in a non-volatilized solid by ionizing gas particles impinging upon said solid.
2. The process of rapidly producing high vacua in vessels, which consists in subjecting them to a suitable preliminary, mechanical exhaustion and absorbing the residual gas in a non-volatilized, gas-absorbing solid by ionizing gas particles contacting therewith.
3. The process of rapidly producing high

vacua in a vessel containing a non-volatilized gas-absorbing solid, which consists in subjecting the vessel to a suitable preliminary, mechanical exhaustion and then ionizing gas particles in the vessel to accelerate absorption of the residual gases by the said solids.

4. The process of rapidly producing high vacua in a vessel, which consists in connecting the same to an auxiliary vessel containing a non-volatilized gas-absorbing solid, subjecting the former and latter vessel to a suitable preliminary, mechanical exhaustion, and then ionizing gas particles in the auxiliary vessel to accelerate absorption of the residual gas by the said solid.

5. The process of rapidly producing high vacua in an incandescent lamp containing a non-volatilized gas-absorbing solid, which consists in subjecting the lamp to a suitable preliminary, mechanical exhaustion, and then working the filament meanwhile, and then bringing the filament to intensive incandescence to accelerate absorption of the residual gas by the said solid.

6. The process of rapidly producing high vacua in a vessel containing charcoal, which consists in subjecting the vessel to a suitable, preliminary exhaustion, and then passing a suitable electric current through the vessel to accelerate absorption of the residual gas by the said carbon solid.

Signed at New York city, in the county of New York and State of New York, this 10th day of March, A. D. 1910.

CHARLES J. THATCHER.
